LOOM SHUTTLE

Philip L. Spencer, Millbury, Mass., assignor to
 Watson-Williams Manufacturing Company,
 Millbury, Mass., a corporation of Massachusetts

Application November 22, 1937, Serial No. 175,820

3 Claims. (Cl. 139—221)

This invention relates to loom shuttles and more particularly to shuttles of the self-threading type, such as are used in automatic weft-replenishing looms.

- 5 It is the general object of my invention to improve the construction of such shuttles in such manner that the life of the shuttle will be prolonged and the performance thereof will be rendered more satisfactory.
- 10 To the attainment of this object, I provide improved means to guide the weft thread as it leaves the shuttle eye and to prevent excessive wear of the shuttle adjacent said eye. By the provision of such means, I avoid the weft breakage previously common in shuttles in which excessive wear adjacent the shuttle eye had taken place.
- 15 My invention further relates to arrangements and combinations of parts which will be hereinafter described and more particularly pointed out in the appended claims.

Preferred forms of the invention are shown in the drawing, in which

Fig. 1 is a side elevation of a self-threading shuttle embodying my improvements;

20 Fig. 2 is a sectional end elevation, taken along the line 2—2 in Fig. 1;

Fig. 3 is a partial sectional plan view, taken along the line 3—3 in Fig. 1;

Fig. 4 is a front elevation of a guide plate, 25 looking in the direction of the arrow 4 in Fig. 3; Fig. 5 is an end view, looking in the direction of the arrow 5 in Fig. 4;

Fig. 6 is a sectional elevation, taken along the line 6—6 in Fig. 4;

30 Figs. 7 and 8 are views similar to Fig. 4 but showing slightly modified constructions; and

Fig. 9 is a partial side elevation of a different type of self-threading shuttle, having a guide-plate corresponding to the construction shown in Fig. 7.

Referring to Figs. 1, 2 and 3, I have shown a portion of a shuttle S having a metal threading block 10 mounted near the front end thereof, which block has a depending portion 11 cooperating with a horn 12 to provide a thread passage 14 through which the weft thread enters the delivery outlet 15.

50 Pins 16 and 17 of steel, glass or porcelain are inserted at the two sides of the delivery passage 15. The pin 16 resists the wear of the weft thread as the shuttle is moving to the right in Fig. 1. As the thread leaves the pin 16, it is drawn over a shoulder, which in the usual construction is formed in the wood of the shuttle body at the end of a thread groove 19.

Certain kinds of weft and particularly rayon cause excessive wear of surfaces over which they are drawn, and such wear on the wood shoulder adjacent the pin 16 causes the shoulder to become badly worn and deeply grooved, so that the weft thread is often caught and broken thereby.

In my improved construction, I provide a guide plate 20 which is mounted in a correspondingly shaped recess in the shuttle body immediately to the left of the pin 16, as clearly shown in Figs. 10 and 3. The guide plate 20 is formed as an elongated plate 21 which is concave in cross section, as clearly shown in Fig. 5.

The right-hand end of the plate, as viewed in Fig. 3, is also curved rearwardly as indicated at 15 24 and is provided with a flat rearward extension or flange 25. In its middle portion, the guide-plate 20 is rearwardly offset or dished as indicated at 26 to provide a depressed portion in which the head of a screw 27 is seated. The screw 27 is 20 the usual binding screw provided for securing the threading block 10 in its recess in the shuttle body.

The groove 19 varies somewhat in its vertical position with reference to the screw 27. To 25 accommodate such variations, I have provided the alternative constructions shown in Figs. 4, 7 and 8. In Fig. 4 the recessed portion 26 is below the center of the plate 20, while in Fig. 7 the recessed portion 30 is symmetrical with the plate 31, and 30 in Fig. 8 the recessed portion 40 is above the center of the plate 41.

In Fig. 9 I have shown the plate 31 mounted in a self-threading shuttle S' having a threading eye of slightly different construction. In the 35 shuttle S', the lower portion of the threading passage 60 is formed between adjacent portions 61 and 62 of the wood shuttle body, guide-pins 63 being provided on each side of the delivery outlet 64. Furthermore, the groove 65 is lower than 40 in the shuttle S, so that the screw 27 is horizontally aligned therewith, permitting the use of the symmetrical guide-plate shown in Fig. 7.

Having described the details of construction of my invention, the use and advantages thereof will be readily apparent. The weft W (Fig. 3) passes from the guide-pin 16 in an easy curve over the portion 24 of the guide-plate 20, which guide-plate is concavely grooved lengthwise and thus provides the necessary clearance to receive the thread between the guide plate and the adjacent side of the shuttle box.

The guide plate is preferably formed of sheet metal which is relatively hard and which will receive and retain a high polish. Thus con- 55

structed, the guide plate will resist the wear of the thread throughout the life of the shuttle, and the cutting or grooving of the shuttle body adjacent the shuttle eye is effectively prevented.

5 My improved guide plate not only possesses the advantages above outlined, but also provides a more firm and substantial seat for the head of the screw 27 which retains the threading block in position in the shuttle body.

10 Having thus described my invention and the advantages thereof, I do not wish to be limited to the details herein disclosed, otherwise than as set forth in the claims, but what I claim is:—

1. In a self-threading loom shuttle having a 15 thread groove in its side surface, a threading block, a cross screw to secure said block in the shuttle body, a threading slot and a side outlet for the thread, that improvement which consists in providing a guide-plate for the thread as it is 20 drawn from said outlet along said thread groove, said guide-plate having a rearward countersunk 25 projection which extends into the body of the shuttle and receives the head of said cross screw below its thread-engaging surface and which provides a firm and enduring seat therefor.

2. In a self-threading loom shuttle having a thread groove in its side surface, a threading block, a cross screw to secure said block in the shuttle body, a threading slot and a side outlet for the thread, that improvement which consists in providing a guide-plate for the thread as it is 5 drawn from said outlet along said thread groove, said guide plate being horizontally elongated and being concave in vertical cross section to correspond to said thread groove, and being rearwardly curved in horizontal cross section adjacent said thread outlet.

3. In a self-threading loom shuttle having a thread groove in its side surface, a threading block, a cross screw to secure said block in the 15 shuttle body, a threading slot and a side outlet for the thread, that improvement which consists in providing a guide plate for the thread as it is drawn from said outlet along said thread groove, 20 said guide plate being horizontally elongated and being concave in vertical cross section to correspond to said thread groove and being provided with a rearwardly extending flange at the end thereof adjacent said thread outlet.

PHILIP L. SPENCER. 25
